ORE REDUCING MACHINE

Alvah D. Hadsel, Oakland, Calif., assignor to
Monarch Development Company, Ltd.

Application May 4, 1931, Serial No. 534,949

28 Claims. (Cl. 83—46)

The present invention relates to ore reducing machines and its principal object is to provide a machine of the character described that is simple in construction, economical in operation and that will reduce the cost of reducing ore to a minimum, and thereby will make much low grade ore available for commercial exploitation that thus far has been considered as being impossible of commercial use at a profit.

More particularly it is proposed in the present invention to use a comparatively simple machine in which the ore may be fed without preliminary crushing and which in a simple continuous operation reduces the ore to any size desired.

It is further proposed in the present invention to use the ore itself as a reducing means and to effect reduction by impact of ore against ore so that the metallic parts of the machine are not subjected to heavy wear due to impact in the crushing operation.

It is further proposed in the present invention to control the fineness to which the ore is to be reduced by hydraulic classification, and thus to combine the principles of ore reduction and classification into a single machine.

Further objects and advantages of my invention will appear as the specification proceeds.

The preferred form of my invention is illustrated in the accompanying drawing in which

Figure 1 shows a top plan view of my machine;

Figure 2 a central longitudinal section taken along line 2—2 of Figure 1; and

Figure 3 a transverse section taken along line 3—3 of Figure 2.

While I have shown only the preferred form of my invention, I wish to have it understood that various changes or modifications may be made within the scope of the claims hereto attached without departing from the spirit of the invention.

In its preferred form my invention comprises a tank 1 adapted to hold water and the ore to be reduced and a large wheel 2 mounted on the shaft 3, which latter is supported in suitable bearings 4, the bearings being arranged so as to allow a lower section of the wheel 2 to be submerged in the water of the tank, the level of which is indicated at 5. The wheel 2 is arranged with a plurality of peripheral buckets 6, each bucket being fixed relative to the wheel, rectangular in cross section, and having a closed bottom 7, closed sides 8, and a closed outer wall 9, while the inner wall is open as shown at 10 with the exception of a small bar 11 rising from the bottom 55 and intended to delay the discharge of the bucket

to some extent. The outer wall 9 is made slanting so that its extreme end 12 is spaced from the bottom 7 of the adjacent bucket and forms an opening therewith as shown at 13, through which water may be admitted into the bucket as the latter passes through the same. The action of these buckets is particularly well illustrated in Figure 3 from which it appears that in passing through the tank the water is scooped into the individual buckets and passes through the buckets in intimate contact with the ore, and rises with the latter to an elevation substantially on a level with the axis of rotation, whereupon the ore and the water discharge through the open inner walls of the buckets, the discharge being distributed through a period of rotation slightly in excess of ninety degrees.

The tank 1 which is rather elongated in form to accommodate the lower section of the revolving wheel is formed with an elevated side pocket 14, the bottom of this side pocket being defined by a substantially semi-circular plate 15 mounted concentrically with the axis of rotation, and extending into the wheel, inside of the buckets so that ore may be fed from this plate into the buckets through their inner openings indicated at 16. The semi-circular plate 15 has an extension 17 projecting still further into the wheel so that its most advanced wall 18, which is slightly bent at its upper end as at 19, comes almost in contact with the plate 20 which entirely closes the far side of the wheel. This extension is formed with a flat bottom 21 positioned above the lower portion of the semi-circular side pocket so that the ore dropping from the buckets first falls on the plate 21 and from there drops sidewise upon the semi-circular plate 15, which latter returns the ore into the buckets. It should be observed that during the operation of this machine a bed of ore gathers on the plate 21 as well as on the plate 15, and that the ore dropping from the buckets therefore makes impact against the ore lying on the plate 21 so that the breaking up of the ore is due to impact of rock against rock, while the metallic portions of the machine are not subjected to the impact and are protected by the superimposed ore.

Additional ore may be admitted upon the semi-circular plate 15 from a chute 22 through a gate 23, while additional water may be admitted through a suitable pipe connection indicated at 24.

It will be noted that three sides of the tank are slightly higher than the fourth side 25 so that as the water rises it overflows over the fourth

side upon the plate 26, and from there to other plates indicated at 27 and 28.

Rotary motion may be imparted to the shaft 3 in any suitable manner as by a train of gears 5 indicated at 29, 30 and 31 from a power shaft 32.

In operation the ore is fed into the machine through the gate 23, and water through the pipe 24. The ore drops on the semi-cylindrical plate 15 and from there into the buckets 6 through the

10 inner openings indicated at 10. During the beginning of the operation with a new machine, a certain amount of rock will of course drop toward and settle in the bottom of the tank to form a

15 bed 33 substantially of the form shown in Figure 3, which latter bed after having been formed, may remain undisturbed for a long period of operation, its surface being continuously scraped by the revolving buckets. The ore, having dropped from the semi-circular plate 15 into the buckets

20 is then lifted as illustrated in Figure 3, the ore gradually shifting in the buckets and beginning to drop as each bucket passes the horizontal center line of the wheel. During the next quarter of revolution, the ore from each bucket drops upon

25 the plate 21 on which a bed of ore remains to serve as an impact means for the dropping ore. It is at this point where the principal crushing and breaking up operation takes place, and each time a rock is dropped from one of the buckets

30 from the bed of rocks on the plate 21, small particles will separate from such rock so that each rock is gradually broken up into fine particles. From the plate 21 the ore passes onto the lower

35 semicircular plate 15, which latter returns the ore to the buckets 6 where it again begins its upward travel.

The fineness to which the ore is to be reduced is controlled by hydraulic classification. Since additional rock and additional water is fed into

40 the tank 1 continuously, there is a continuous overflow of the water and the lighter particles of ore are carried off with the overflow to pass over the plates 26, 27 and 28, to be discharged from the latter. All the ore entering through

45 the gate 23 is broken up in the machine until reduced to a size capable of being carried off by the overflowing water so that the fineness of reduction can be closely regulated by adjustment of the height of the wall 25 and by the rate of

50 water feed.

I claim:

1. A stationary tank for holding water, an impact medium above the water, spaced means with passages therebetween for passing a quantity of ore through the water, for elevating the quantity and dropping the same on the impact medium and means for returning the ore from the impact medium to the water.

2. In an ore reducer, a stationary container 60 for holding water, a wheel revolvably mounted with its lower portion submerged in the water, ore-carrying buckets on the wheel adapted to dip into the water and to receive ore while passing through the water and to drop the ore when

65 raised and a breaker plate mounted within the wheel and above the water so as to form an impact medium for the dropping ore, the breaker plate having a free edge communicating with the water to allow the ore to gravitate over the free

70 edge through the water to the submerged buckets.

3. In an ore reducer, a stationary container for holding water, an elevator mounted with its lower portion submerged in the water, ore-carriers on the elevator adapted to pass through the 75 water, to receive ore while thus passing and to

drop the ore when raised and a breaker plate mounted above the water and so as to form an impact medium for the dropping ore, the breaker plate having a free edge communicating with the water to allow the ore to gravitate therefrom over the free edge through the water to the submerged ore-carriers.

5

4. In a device of the character described, a stationary tank for holding a liquid and having a discharge edge, an impact medium mounted above the liquid and having a free edge communicating with the latter, a revolvable wheel having its lower portion submerged in the liquid, buckets on the wheel for lifting material from the liquid and dropping the same on the impact medium 10 whereby the material is crushed and made to gravitate over the free edge of the impact medium into the liquid, the wheel having one side closed for maintaining a comparatively quiet zone between the wheel and the discharge edge 15 of the tank and means for floating the lighter particles of material toward the quiet zone and thence over the discharge edge.

10

5. In a device of the character described, the combination with a stationary tank containing 25 liquid and having an edge over which the liquid discharges, of means for dropping crushed material into the liquid, means for maintaining a quiet zone in the portion of the tank adjacent the discharge edge and means for floating off the finer 30 particles of the material through the quiet zone and over the discharge edge.

25

6. In a device of the character described, a revolvable wheel having peripheral buckets thereon opening internally and externally in the direction 35 of rotation, means for mounting the wheel on a horizontal axis, means for feeding ore into the lower buckets, an impact medium mounted within the wheel to receive ore dropping from the ascending buckets and means for returning the 40 ore from the impact medium to the lower buckets in the vertical plane of the dropping ore.

35

7. In a device of the character described, a revolvable wheel having peripheral buckets thereon opening internally and externally in the direction 45 of rotation, means for mounting the wheel on a horizontal axis, means for feeding ore into the lower buckets, an impact medium mounted within the wheel to receive ore dropping from the ascending buckets and means for returning the 50 ore from the impact medium to the lower buckets in the vertical plane of the dropping ore in combination with means for classifying the returning ore for removal of the fines.

45

8. In a device of the class described, the combination with a stationary tank containing water, of a wheel revolvably mounted with its lower portion submerged in the water in the tank, buckets on the wheel adapted to dip into the water and to receive material while passing 60 through the water and to drop the material when raised a predetermined amount above the water, and stationary impact means mounted within the revolvable wheel and in the path of the material discharged from the buckets, the impact means 65 being disposed above the level of the water in the tank so that the falling material is intercepted and crushed, said impact means having a free edge communicating with the water in the tank to allow the crushed material to gravitate 70 through the water to the submerged buckets.

65

9. A device of the class described comprising a rotatable wheel having a series of buckets extending around its periphery with the front portion of one bucket abutting the rear of the ad- 75

5 jacent bucket, the rear end wall of each bucket being closed and an opening formed between the rear end wall and the bottom of the adjacent bucket, and an opening formed in the portion 10 of each bucket facing the interior of the wheel.

10 10. A device of the class described comprising a rotatable wheel having a series of buckets extending around its periphery with the front of one bucket abutting the rear of the adjacent 15 bucket, the bottom of each bucket extending outwardly at an angle to the periphery of the wheel, the rear end wall of each bucket being closed and of less height than the front of the adjacent bucket.

15 11. A device of the class described comprising a rotatable wheel having a series of buckets extending around its periphery with the front of one bucket abutting the rear of the adjacent bucket, the bottom of each bucket extending outwardly at an angle to the periphery of the wheel, the rear end wall of each bucket being closed and of less height than the front of the adjacent bucket, an annular plate enclosing one side of the buckets, said plate having an opening formed 20 25 therein to provide an open side for the wheel interiorly of the buckets, and a solid plate enclosing the opposite side of the buckets and wheel.

12. In a device of the class described, the combination with a stationary tank having a discharge outlet, of a rotatable wheel having a series of buckets on its periphery adapted to be successively submerged in the liquid in the tank when the wheel rotates, said wheel having one end closed and its opposite end open, the closed end 30 35 portion of the wheel being located adjacent to the discharge outlet of the tank, means for delivering material and liquid into the tank at the open side of the wheel, and a fixed material breaker medium disposed within the wheel and overlying the liquid in the tank, said breaker medium being adapted to intercept material discharged from the raised buckets, one edge portion of the breaker medium communicating with the liquid in the tank and the opposite edge portion of said breaker medium being closed by the closed end wall of the wheel.

13. In a device of the class described, the combination with a stationary tank containing liquid and material, of a rotatable wheel having its lower portion submerged in the liquid in the tank, buckets carried by the wheel for lifting material out of the tank, said wheel having one end closed and its opposite end open, means for delivering material into the tank at the open end portion of the wheel, and a fixed impact plate disposed within the wheel and overlying the liquid in the tank, said plate being adapted to intercept material discharged from the buckets, one edge portion of the impact plate being disposed adjacent to the open side of the wheel and being in communication with the liquid in the tank and the opposite edge portion of said plate being closed by the closed end wall of the wheel.

14. A device of the character described comprising a revolvable drum having a plurality of material lifting means thereon, means for feeding material into said drum, means associated with the drum for receiving the impact of the material discharged from said lifting means, means for discharging the material from such a height that the material falling onto said impact means is substantially chipped, the lifting means being arranged closely together for discharging the material in substantially parallel streams, 60 65 70 75 means formed on the drum for confining the ma-

5 terial therein to a substantially narrow zone and for preventing movement of the material axially through the drum, the impact means having an area corresponding substantially to the area of the stream of falling material so as to intercept substantially all of the material falling from the lifting means, means for returning the material from the impact means to the lifting means in the bottom of the drum, and fluid means for separating the fines from the material undergoing 10 reduction in the device.

15. A device of the class described comprising a rotary drum having a diameter not less than four times its width, in combination with means for feeding material into one side of the drum, 15 means for lifting the material, means for receiving the impact of the material, means for gradually discharging the material from said lifting means whereby the material collects on to the impact means in the form of a shallow bed, means 20 for returning the material from the impact means to the lifting means through the same side of the drum through which the material enters the drum, and fluid means for classifying the material. 25

16. In an ore reducer of the character described, a revolvably mounted wheel having peripheral buckets thereon with openings toward the center of the wheel, and having outer walls presented angularly relative to the wheel for 30 scooping action the front edge of the outer wall of each bucket being in radial alignment with the rear edge of the preceding bucket.

17. In a device of the character described, a stationary tank for holding a liquid and having 35 a discharge edge, an impact medium mounted above the liquid and having a free edge communicating with the latter, means for dropping material on the impact medium whereby the material is made to gravitate into the liquid in 40 comminuted form, means for maintaining a comparatively quiet zone between the impact medium and the discharge edge of the tank through which all of the finer particles of the material are caused to pass, and means for floating off the 45 finer particles of the material over the discharge edge of the tank.

18. A device of the class described comprising a rotary drum, means for feeding material into one side of said drum, means carried by the 50 drum for lifting the material, means for gradually discharging the material across said drum, means spanning the drum substantially from side wall to side wall for receiving the impact of the material discharged from said lifting means, the 55 drum having a closed end for confining the material therein to a substantially narrow zone, means for returning the material from the impact means to the lifting means, and means for separating the fines. 60

19. A device of the class described comprising a revolvable drum having a plurality of material lifting means, means for feeding material into one side of said drum, means formed on the drum for preventing movement of the material 65 axially through the drum, an impact medium mounted within the drum and spanning substantially the space between said material lifting means, means for gradually discharging the material from said lifting means in substantially 70 uniform streams across the drum, and means for removing the fines from the material undergoing reduction in the device.

20. A device of the class described comprising a revolvable drum, means formed on the drum 75

- for lifting the material, means for feeding material into one side of the drum, means for preventing movement of the material axially through the drum, impact means for receiving the thrust of the material discharged from said material lifting means, said impact means being mounted near the bottom of the drum and spanning substantially the space between said material lifting means, means for discharging the material from the lifting means in substantially uniform streams across the drum whereby the material falls in a substantially uniform layer on said impact means, and means for separating the fines after each impact of the material with said impact means.
21. A device of the class described comprising a revolvable drum, a plurality of buckets mounted in the drum for lifting the material, means for feeding material into one side of said drum, means for preventing movement of the material axially through the drum, impact means for receiving the impact of the material discharged from said buckets, said impact means being mounted near the bottom of the drum and spanning substantially the space between said buckets, means for discharging the material from the buckets in substantially uniform streams across the drum whereby the material falls in a substantially uniform layer on said impact means, and means for separating the fines after each impact of the material with said impact means.
22. A device of the character described comprising a revolvable drum having one side closed and an opening formed in its opposite side, a plurality of buckets mounted around the periphery of the drum for lifting the material, means for feeding the material into said drum through the open side thereof, an impact medium mounted a substantial distance below the axis of the drum for receiving the impact of the material discharged from said buckets, said impact medium extending transversely across the drum, means for gradually discharging the material from the buckets whereby the material falls on the impact medium in substantially uniform streams, and means for separating the fines after each impact of the material with said impact medium.
23. A device of the character described comprising a revolvable drum, a plurality of material lifting buckets carried by said drum, an opening formed in one end wall of the drum, a wall formed at the opposite end of the drum for preventing axial movement of the material through the drum, means for feeding the material into said drum through the open end thereof, impact means within the drum for receiving the thrust of the material, said impact means spanning substantially the interior of the drum from the buckets on one side to the buckets on the opposite side, means for discharging the material from the buckets in substantially uniform streams across the drum, whereby the material falls in a substantially uniform layer on said impact means, and means for separating the fines after each impact of the material with said impact means.
24. In an ore reducing machine, means for repeatedly subjecting the ore at spaced intervals to crushing action in a closed circuit in which unreduced portions of the ore are prevented from leaving the circuit and means for moving the ore after each crushing action through a stationary body of water with the ore exposed to the washing action of the water for washing out the fines.
25. In an ore reducing machine, means for repeatedly subjecting the ore at spaced intervals to crushing action in a closed circuit in which unreduced portions of the ore are prevented from leaving the circuit and means for moving the ore after each crushing action through a stationary body of water with the ore exposed to the washing action of the water for washing out the fines, the latter means having openings allowing concentrates to settle out of the circuit.
26. A device of the class described comprising a revolvable drum having a plurality of material lifting means, means for feeding material into said drum, means formed on the drum for preventing movement of the material axially through the drum, an impact medium mounted within the drum and spanning substantially the space between said material-lifting means, means for gradually discharging the material from said lifting means in substantially uniform stream across the drum, and means for removing the fines from the material undergoing reduction in the device.
27. In an ore reducing machine, means for repeatedly subjecting ore at regular and timed intervals to crushing action in a continuous and closed circuit in which unreduced portions of the ore are prevented from leaving the circuit and are confined to a restricted zone, and means for hydraulically classifying the ore by flotation in water during the interval after each crushing action for removal of the fines, the latter means including a settling area for concentrates contained in the ore.
28. In an ore reducing machine, a tank for holding water, a breaker plate supported above the water, a bucket elevator encircling the breaker plate and being narrower than the tank, and having its lower buckets submerged in the water with front sections of the buckets open to the water, means for feeding material into the buckets whereby the material is raised and dropped on the breaker plate and made to gravitate from the plate into the water in comminuted form, the fines being made to float on the water while the coarser particles descend into the buckets for further elevating and dropping, and the water circulating from the tank through the open front sections of the buckets toward the interior of the elevator and back again on the outside of the elevator.

ALVAH D. HADSEL.
